CONTACT MAKING WIRE CLAMP

Hugh H. Eby, Jenkintown, Pa.

Application June 29, 1940, Serial No. 343,122

5 Claims. (Cl. 173—340)

This invention relates to contact-making wire clamps or connectors, and particularly to such devices as are generically designated binding posts.

With the developments of wire communications, especially in the art of war, it has become increasingly important that wire communication once established, be maintained, substantially regardless of the vicissitudes to which the wires are subjected.

This has not yet become absolutely true, as it has been discovered that certain of the earlier forms of connectors established satisfactory electrical connection with wire only as long as nothing strained the wire. As soon as a soldier, or other moving object, imposes such stress on the wire as to cause it to be subjected to appreciable longitudinal pull, such previous connectors either loosened the grip on the wire, or else as a result of the pull lost the electrical contact therewith, even though the wire might still be relatively anchored. Moreover such connectors after such wire pull were no longer available for subsequent fastening of other wires, as they had themselves suffered distortion militating against such use.

It is among the objects of this invention to provide a cheap and rugged contact-making wire clamp; to provide a wire clamp arranged for easy and facile attachment; to provide a wire clamp arranged to establish an intimate electrical contact with any sort of wire, whether insulated or uninsulated; to provide a wire clamp with gripping means guided and supported against lateral distortion as a result of wire pull; to provide a wire clamp arranged to center the wire to be clamped to facilitate engagement and electrical contact; to provide a wire clamp with gripping means larger in cross section than the wire to be gripped in one part and as large as the wire in the other part to insure tight grip thereon; to provide a wire clamp with gripping contact-making members of such reinforced construction that even though under great pull a wire might be moved laterally of the clamp, the electrical contact will be maintained; to provide a wire clamping device having a single unitary member arranged both to clamp and to penetrate the insulation of a wire to establish electrical contact; to provide a wire clamp with an insulation and wire piercing gripping member, and many other objects and advantages will become more apparent as the description proceeds.

In the accompanying drawing forming part of this description:

Fig. 1 represents a longitudinal transverse section through the assembled clamp of this invention according to a preferred embodiment thereof in which regardless of its lower surface contour there is a vertical and a horizontal slot.

Fig. 2 represents a transverse section therethrough on line A—A of Fig. 1.

Fig. 3 represents a front elevation, partially in section through the device of Fig. 1 with a fragment of wire gripped therein showing its distortion under pressure.

Fig. 4 represents a fragmentary section through a modified form of the clamp, showing a V shaped bottom of the slot.

Fig. 4A represents a fragmentary elevation partially in section of the clamp of Fig. 4 with an insulated wire pierced and gripped thereby.

Fig. 5 represents a fragmentary section of a further modified form of clamp showing a single inclined slot in place of the compound slot of Fig. 1.

Fig. 6A represents a fragmentary elevation, in part section, of the clamp of Fig. 6 gripping a wire.

Figs. 6 and 7 represent respectively fragmentary elevations partially in section of a clamp according to Fig. 1 engaging, establishing contact with, and gripping an insulated wire and a smaller bare wire, to show the operation of the device, with the cap removed for clarity.

Fig. 8 represents a fragmentary elevation, partially in elevation of a clamp having a blunt-ended stud engaging a relatively thick wire, in an initial stage of compression.

Fig. 9 is a view similar to Fig. 8, showing the anchored engaged relation of the parts to a stranded wire.

Fig. 10 represents a fragmentary longitudinal section through a modified form of clamp.

The wire-gripping electrical connector preferably comprises a unitary device having no disconnectible parts, so as to facilitate use of the connector for military purposes. In the purely illustrative device shown in Fig. 1, which will be relied upon for the broad purposes of disclosure, but which is obviously susceptible to wide variations in actual construction, some of which will be pointed out later herein, a solid integral base 10 is provided, having a lower terminal end 11 preferably comprising a threaded shank, leading into the flange 12. A generally hollow cylindrical element 13 extends axially of the flange 12 opposite to the threaded shank 11, and the outer free end 14 thereof is preferably completely cylindrical in a closed cylinder having an internal

axial bore 15, and having the external threads 16. The side of element or base 10 has a transverse relatively horizontal or lateral slot opening 17 forming an entrance for wires, which communicates with the through axially elongated relatively vertical transverse slot 18 of such extent axially of the base as to form an internal arcuate or other lower shoulder or abutment 20 immediately below the slot opening 17 to prevent undesired lateral withdrawal of wires after disposition in the slot 18. In the preferred embodiment the axial bore 15 in the base is prolonged axially across the axial transverse slot 18 and terminates in a flat ended seat depression or hole 21, and the bore is preferably of greater diameter than the width of slot 18 and is preferably symmetrical thereof. The flat surface of the seat depression 21 may be at any other point but is preferably substantially tangential to the preferably arcuate lower surface 22 of the vertical or axial slot 18. In order to firmly anchor the base in whatever it may ultimately be secured and to hold it against rotation, a pin 23 is provided extending from the lower surface of the flange 12. In the preferred embodiment the flat seat depression 21 has a concentric recess 24 extending across the flange line into the shank 11, if the length of the pin to be described should be such as to require it.

In the parts so far described it will be clear that as the vertical transverse slot 18 has a lower end which is arcuate, or as will be shown later of V or other convergent relation, while the seat depression 21 formed of the flat lower surface and the continuation of the sides of the bore 15 intersecting said flat surface is substantially rectangular in lateral cross section, the intersection of the sides of the depression 21 with the slot 18 will form generally vertical shoulders 25 substantially transverse of slot 18 for a purpose to be described.

In the modification of the base element shown in Fig. 4 all of the parts are preferably the same as has just been described, except that the slot 18 has angularly divergent walls, respectively 26 and 27, meeting in an apex at the lower end of the slot as at 28.

In the further modification shown in Fig. 5, the compound slot shown in Figs. 1 and 4 comprising the horizontal slot opening 17 and the vertical slot 18, has been formed as the inclined slot 30, as a form into which wires can be placed readily and easily locked, and which under some circumstances might be considered as easier to fabricate with the machinery available. The operation of this slot will become more evident as the description proceeds.

Returning now to Fig. 1 there is shown in section an externally knurled hollow cap 31 internally threaded as at 32 so as to threadably engage the threads 16 of the base 10, having the depending bendable flange 33 preferably bent about the external surface of the element 10 below the threads 16 so as to form a positive stop to the removal of the cap. A stud 34 preferably, although obviously not essentially integral, depends from the end of the cap to termination in a preferably substantially flat end 35 and is arranged to move downwardly in the bore 15 of the base, shearing across the shoulders 25 to seat in seat depression 21. The stud is preferably such as to have a sliding but guided laterally reinforcing fit in the bore 15. In one form of the invention the stud end is finished substantially flat as shown in Figs. 8 and 9 and the operation of 75

the invention in such a manner as to engage suitable wires will be described. However it is preferred to mount an axially extending pointed pin 36 in the flattened end or to continue the stud 5 in an integral continuation in such pin if desired. It will be clear that the pin 36 will normally seat in the recess 24 in the seated or closed cap position.

In the fragmentary views which will now be 10 described it will be assumed that wires of various characteristics will have been inserted in the respective slots and have been engaged by the end of the studs, both with and without the elongations in the form of pins.

15 Assuming that the wire 38 to be engaged is of small gauge but with heavy insulation 40, the operation will be as shown in Fig. 6 in which with the wire moved laterally through slot opening 17 into slot 18, the cap will be turned to force the 20 end of the stud against the wire, and the wire will be centered in the slot by the convergent walls (whether arcuate or angular), the pointed pin will be forced through the insulation into the wire 38 to establish intimate electrical contact 25 of the wire and the connector while simultaneously the blunt or squared end 35 of the stud will have engaged the insulation 40 and begun to crush it, causing it in effect to "flow" downwardly toward the seat depression 21, and laterally into 30 the bore extension, across shoulders 25, disposed substantially transversely of the wire, exerting shearing action to dig the shoulders 25 into the insulation while forcing the insulation into the spaces or depression 21 behind the shoulders, as 35 shown in dotted lines in Fig. 6A to firmly anchor the wire to the connector by enhanced frictional effects between the parts. If the pressure is sufficiently great the crushing of the insulation will be imparted to the wire to distort it out of 40 its initial concentric alignment to contribute to the increased frictional gripping of the parts. The forcing of the pin 36 through the insulation and into the wire will cause some distortion of both insulation and wire to enhance the interlocking relationship.

It is contemplated that in many instances the wire will first be scraped of insulation as shown in Fig. 7, in which event the pin 36 will assist in pushing the wire toward either the front or the rear of the vertical slot while permitting the flattened end 35 to exert its crushing contact-making anchoring function. In certain cases where it is known that wires of small gauge are to be encountered a pin of larger base may be 55 used to so crowd the wire laterally as to force it more certainly over the shoulders of the contact seat. In the alternative similar results are achieved by simply making the seat depressions 21 deeper to a position parallel to the tangential, 60 and in this case there is no interruption of the vertical shoulders and each wire is given a certain amount of shearing stress. As it is not desired to cut the wires off, the exposure to shoulder shearing stress will be limited to a degree 65 not more than that required to merely bite into the wire. In the case of insulated multiple strand connectors, cables or wires the ability of the pin to penetrate and anchor the strands, instead of pushing them aside as in the last described figure, will be obvious.

In the case of the V-shaped bottom to the slot 18 it will be evident that the descending pin will penetrate the small insulations as well as the large centrally of both to engage the concentric wire within the insulation while the convergent

walls will receive both large and small insulated as well as scraped or uninsulated wires.

The analogous functioning of the forms of the invention which have no pins will be clear, but for convenience reference may be made to the fragmentary disclosure of Fig. 8 in which a large bare wire 41 is shown as being engaged by the connector. The shearing stresses, the enhanced frictional "bite" attaching thereto, will be clear. An analogous operation upon bare stranded wire 42 is indicated in the fragmentary disclosure of Fig. 9.

It is a further feature of the invention under desired conditions to utilize the flange 33 on the knurled cap 31 to engage and exert shearing stress upon that portion of the wire extending laterally from the connector as the stud is doing the same centrally of the base, to enhance the frictional grip on the wire, as shown in Fig. 3.

The important result of maintenance of complete electrical contact despite any lateral slippage of the wire relative to the connector is secured by the invention, and the quickness of operation and attachment, the freedom from use of multiple parts for the purpose, and the strength of the assembly will be obvious. It is to be remembered that with the stud guided in the bore leading right to the upper surface of the slot 17, the stud and therefor the pin is laterally supported and held against lateral distortion even though enough pressure is exerted on the wire longitudinally as to pull the wire along in the connector. This is very important.

Referring to Fig. 10 a slight modification is shown with a base 10' having a lower portion formed like any of the preceding figures (illustratively like Fig. 1) having an anchoring stud 11', flange 12', horizontal slot 17', vertical slot 18', cylindrical extension 13', and a bore extension seat 21'. The cylindrical extension 14' has 40 a bore 15' to receive and guide an anchoring stud 34' having the lower substantially flat end 35' and sharpened extension 36' arranged to seat in seat depression 21', and the upper end of stud 34' is threaded as at 41' and engages threads 45 42' in the upper portion of the extension, separated from bore 15'. A knurled cap 43 on the upper end of the stud enables it to be moved axially of the base in a manner similar to and with a result analogous to that of Fig. 1 for instance.

It will be understood that the flange 33 of the cap 31 of Fig. 1 may terminate at any level relative to the termination of the internal stud 34 or point 36, so as to augment the grip on the 55 wire by compressing it in shear against the bottom of the slot 18 at the ends of the slot, if this is desired, or to merely serve to hold the cap on the base without any appreciable contact with the clamp-engaged wire.

I claim as my invention:

1. A contact making wire clamp consisting of two members mounted in telescopic relation, one of said members being relatively fixed and having a slot, a depression, an opening, and a bore, said slot extending transversely through said member and having a substantially arcuate wall at one side, said depression passing through said substantially arcuate wall to form oppositely disposed shoulders, said opening communicating laterally with said slot to permit a wire to enter said slot, and said bore extending axially of said member from the opposite side of said slot from said depression, the other of said members being adjustably mounted on the fixed member and

having a plunger guided by said bore to enter said slot to compress said wire over said shoulders and into said depression to thereby resist endwise movement of said wire, and a piercing pin on said plunger to penetrate said wire.

2. A contact making wire clamp consisting of two members mounted in telescopic relation, one of said members being relatively fixed and having a slot, a depression, a lateral opening, and a bore, said slot extending transversely and communicating with the lateral opening to permit a wire to be inserted into said slot through said opening, the lower surface of the slot being curved to support a wire when in said slot, said bore being of greater diameter than the width of said slot and extending into the slot axially on one side thereof to form axial shoulders therewith, said depression being located in said curved lower surface of the slot on the side axially opposite to said bore and forming shoulders to extend substantially transverse of a wire in said slot and merging into said axial shoulders, the other of said members being adjustably mounted on the fixed member and having a plunger guided by said bore to enter said slot to compress a wire over both sets of shoulders and into said depression and bore extension whereby said shoulders engage the wire to resist endwise relative movement of the wire, and a piercing pin on said plunger to penetrate the wire.

3. A contact making wire clamp consisting of two members mounted in telescopic relation, one of said members being relatively fixed and having a slot, a depression, an opening, and a bore, said slot extending transversely through said member and having a substantially arcuate wall at one side, said depression passing through said substantially arcuate wall to form oppositely disposed shoulders, said opening communicating laterally with said slot to permit a wire to enter said slot, and said bore extending axially of said member from the opposite side of said slot from said hole, the other of said members being adjustably mounted on the fixed member and having a plunger guided by said bore to enter said slot to compress said wire over said shoulders and into said depression to thereby resist endwise movement of said wire.

4. A contact making wire clamp consisting of two members mounted in telescopic relation, one of said members being relatively fixed and having a slot, a depression, a lateral opening, and a bore, said slot extending transversely and communicating with the lateral opening to permit a wire to be inserted into said slot through said opening, the lower surface of said slot being substantially planar in profile on a section longitudinal of the slot and being substantially non-planar in profile with downwardly convergent surfaces on a section transverse of the slot and serving to support a wire when in said slot, said depression being located in said lower surface and having a bottom surface of a different profile from the profile of said convergent lower surface transverse of the slot so as to form shoulders of varying height extending substantially transversely of said slot, said bore extending toward the slot opposite to said depression, the other of said members being adjustably mounted on the fixed member and having a plunger guided by said bore to enter said slot to compress such wire over said shoulders to resist endwise movement of such wire.

5. A contact making wire clamp consisting of two members mounted in telescopic relation, one

of said members being relatively fixed and having a slot, a depression, a lateral opening, and a bore, said slot extending transversely and communicating with the lateral opening to permit a wire to be inserted into said slot through said opening, the lower surface of said slot being substantially planar in profile on a section longitudinal of the slot and being substantially non-planar with downwardly convergent surfaces in profile on a section transverse of the slot serving to support a wire when in said slot, said bore extending toward the slot opposite the depression, said depression being located in said lower surface and having a bottom surface substantially tangential to the downwardly convergent surfaces so that the substantial plane of the profile longi-

tudinal of the slot is substantially maintained across said depression to form an anvil against which the main thrust applied to the wire is received, said depression having walls substantially parallel to the axis of the bore and forming with said lower surface right-angled shoulders of varying height increasing from the point of substantial tangency transversely of the slot, the other of said members being adjustably mounted on the fixed member and having a plunger guided by said bore to enter said slot to compress a wire against the anvil portion and to distort same laterally of the anvil portion into contact with said right-angled shoulders to resist endwise movement of such wire.

HUGH H. EBY.
